[57] CLAIM

The ornamental design for telephone answering instrument, as shown.

DESCRIPTION

FIG. 1 is a top, front and right side perspective view of a telephone answering instrument showing my new design;

FIG. 2 is a top plan view thereof;

FIG. 3 is a right side elevational view thereof, the side opposite being substantially a mirror image thereof except for the omission of the three side buttons; and FIG. 4 is a rear elevational view thereof.

The bottom of the telephone answering instrument is plane and unornamented.

FIG. 1

FIG. 2

FIG. 3

FIG. 4
